(57) **CLAIM**

The ornamental design for an outlet-to-tube connector for positive airway pressure delivery console, as shown and described.

DESCRIPTION

FIG. 1 is a front perspective view of an outlet-to-tube connector for positive airway pressure delivery console showing our new design in a first embodiment;

FIG. 2 is another perspective view thereof showing the connector in isolation;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a rear view thereof;

FIG. 9 is a reverse front perspective view thereof;

FIG. 10 is a front perspective view of an outlet-to-tube connector for positive airway pressure delivery console showing our new design in a second embodiment;

FIG. 11 is another perspective view thereof showing the connector in isolation;

FIG. 12 is a left side view thereof;

FIG. 13 is a right side view thereof;

FIG. 14 is a top view thereof;

FIG. 15 is a bottom view thereof;

FIG. 16 is a front view thereof;

FIG. 17 is a rear view thereof; and,

FIG. 18 is a reverse front perspective view thereof.

The broken lines in the drawings illustrate portions of the outlet-to-tube connector for positive airway pressure delivery console which form no part of the claimed design.

The combination of line shading and stippling is intended to convey a contrast in appearance/materials.

1 Claim, 10 Drawing Sheets
